UNITED STATES PATENT OFFICE

CECIL S. KELLEY, OF EAST MCKEESPORT, PENNSYLVANIA, ASSIGNOR TO THE WESTINGHOUSE AIR BRAKE COMPANY, OF WILMERDING, PENNSYLVANIA, A CORPORATION OF PENNSYLVANIA

SOUND PRODUCER

Application filed June 18, 1930. Serial No. 461,961.

This invention relates to sound producing devices, and more particularly to the type employing a vibratory diaphragm.

Heretofore it has been proposed to equip 5 the flexible diaphragm of sound producing devices with a weight so that a more positive opening and closing movement of the diaphragm will be obtained. One type of sound producing device having a weighted 10 diaphragm is shown in United States Letters Patent No. 1,679,011, of R. G. Widmyer, issued July 31, 1928. In the structure shown in the above mentioned patent, the weight is riveted to the diaphragm, and on each side of 15 the rivet, the surface of the weight facing the diaphragm is cut away on an arc, so as to permit flexing of the diaphragm. With such construction, the arched surface of the weight does not meet the face of the diaphragm tangentially when the diaphragm is flexed away from its normal position. As a 20 result of this, constant vibration of the diaphragm often results in a fracture of the diaphragm at the point where the face of the diaphragm meets the arched face of the weight when the diaphragm is flexed outwardly from its normal position.

It has also been proposed to provide sound 25 producing devices of the type herein referred to with means for limiting the flexing of the diaphragms outwardly from their normal positions, when the diaphragms are vibrated. One type of sound producing device having means for limiting the vibration of the diaphragm is shown in United States Letters Patent No. 1,742,380, of Clyde C. Farmer, issued January 7, 1930.

In the Farmer device, stops are provided 30 at the rear side of the diaphragm. The use of these stops, it has been found, reduces the tone volume considerably, and also destroys the tone quality to a certain extent, and in addition, does not entirely eliminate the diaphragm breakage. Furthermore, the stops 35 may dig into a diaphragm and thus cause breakage at this point.

An object of the invention is to provide a sound producing device having a weighted 40 diaphragm in which the weight is formed

with means for limiting the amount the diaphragm will flex from its normal position.

Another object of the invention is to provide a sound producing device of the above type in which the diaphragm is provided 55 with a weight which is so mounted on the diaphragm as to permit a limited vibratory movement of the diaphragm without causing undue wear to the diaphragm.

Another object of the invention is to provide a sound producing device of the above type in which the diaphragm is provided with a weight which is so mounted on the diaphragm that it provides a stop for limiting the movement of the diaphragm 60 outwardly from its normal position.

Another object of the invention is to provide an improved sound producing device of the character mentioned which is simple in construction, and reliable and exact in function under all conditions of service.

The invention also comprises certain new and useful improvements in the construction, arrangement and combination of the several parts of which it is composed, as will 70 be hereinafter more fully described and claimed.

In the accompanying drawing; Figure 1 is a section of a sound producing device embodying the invention, showing the flexible diaphragm in the normal inoperative position; and Fig. 2 is a view similar to Fig. 1, showing the diaphragm flexed outwardly to 75 illustrate the manner in which the diaphragm engages the weight.

Referring to the drawing, the sound producing device may comprise a casing 6 having a chamber 7, which is open to a flexible diaphragm 8, said diaphragm being clamped in position by a cover plate 9, which is secured to the casing 6 by screws 10.

The casing is provided with a central tube 11, which projects inwardly toward the diaphragm 8. Secured to the tube 11 is a suitable amplifying horn 12. When the parts 80 are assembled, the free end of the tube 11 just engages the face of the diaphragm 8, as shown in Fig. 1.

The chamber 7 is connected to a pipe 13, through which fluid under pressure is sup- 100

plied to said chamber, the rate of flow being governed by a restricted port 14 formed in the casing 6 between the end of the pipe and the chamber.

5 An opening 15 is provided in the cover plate 9, so that the chamber at the outer face of the diaphragm 8 remains at atmospheric pressure at all times.

Secured to the central portion of the diaphragm 8 and extending into the open end of the tube 11, is a weight 16 which is preferably in the form of a truncated cone having its base adjacent to the diaphragm. As shown, the outer portion of the base of the weight 16 is cut away, as at 17, so as to provide a central flat surface 20, of less diameter than the diameter of the base of the weight, for bearing against the inner face of the diaphragm. A stop 18 is formed at the inner end of the undercut portion of the weight, and at the outer periphery of the base of the weight, there is a corner 19, the purpose of which will be hereinafter more fully described.

25 In operation, when fluid under pressure is supplied to pipe 13, fluid flows through the restricted port 14 into chamber 7, and the pressure of fluid in chamber 7 builds up so that the diaphragm 8 is moved outwardly.

30 In moving out, communication is opened from chamber 7 to the space within the tube 11. The pressure in said chamber is then quickly reduced, since the rate of flow through the restricted port 14 is considerably less than the rate of flow from chamber 7 to tube 11. The pressure on the diaphragm 8 being thus relieved, said diaphragm returns to its position engaging the end of the tube 11. The opening movement is then repeated.

35 The diaphragm is thus caused to vibrate and thereby produces a sound which is amplified by the usual operation of the horn 12.

40 The weight 16 makes it necessary for the fluid pressure to be built up to a higher point before the diaphragm will move away from the end of the tube 11, than would be the case with an unweighted diaphragm, but when the diaphragm does move, the higher pressure causes a greater movement of the diaphragm and consequently, a greater amount of potential energy is stored up, so that the return movement of the diaphragm is effected more forcibly.

45 In this action, it is desirable to provide means for limiting the outward movement of the diaphragm 8, so that the rebound of the diaphragm will be damped. This is accomplished by so forming the weight 16, that when the diaphragm moves outwardly, the 50 inner face of the diaphragm will engage the outer edge or corner of the base of the weight, as shown in Fig. 2.

55 It will be noted that the diaphragm travel is small, and therefore the deflection of the 60 diaphragm outwardly, is also small, so that

the inner face of the diaphragm engages the periphery of the base of the weight before the elastic limit of the diaphragm is reached.

Since the diaphragm 8 normally engages the surface 20 of the weight, when the diaphragm moves outwardly and strikes the periphery of the base of the weight, a greater surface of the diaphragm will be engaged, and therefore the movement of the diaphragm is arrested. However, if the force of the diaphragm is great, the diaphragm will deflect slightly further, due to the momentum of the weight, before returning to its normal position. In this way the movement of the diaphragm will be gradually arrested when the periphery of the base of the weight is engaged. Therefore, the use of the periphery of the weight as means for arresting the outward movement of the diaphragm provides a resilient stop, because when the face of the diaphragm engages the corner 19 of the weight, if the force of the diaphragm is great, the diaphragm will be deflected slightly further before returning to its normal position against the inner end of the tube 11.

50 While one illustrative embodiment of the invention has been described in detail, it is not my intention to limit its scope to that embodiment or otherwise than by the terms of the appended claims.

55 Having now described my invention, what I claim as new and desire to secure by Letters Patent, is:

1. A sound producing device comprising a casing having a chamber, a flexible diaphragm subject to the pressure of fluid in said chamber, a vent tube normally in engagement with said diaphragm, a weighted member carried by said diaphragm for regulating the vibratory movement of said diaphragm, and means on the weighted member for dampening the movement of the diaphragm.

100 2. A sound producing device comprising a casing having a chamber, a flexible diaphragm subject to the pressure of fluid in said chamber, a vent tube normally in engagement with said diaphragm and controlling communication from said chamber to said tube, and a weighted member in the form of a truncated cone, for regulating the vibratory movement of said diaphragm away from the tube.

110 3. A sound producing device comprising a casing having a chamber, a flexible diaphragm subject to fluid in said chamber, a vent tube normally in engagement with said diaphragm and controlling communication from said chamber to said tube, and a weighted member mounted on the diaphragm, the face of the member adjacent the diaphragm being undercut to provide means for arresting the movement of said diaphragm when the diaphragm is deflected from said tube.

4. A sound producer comprising a flexible diaphragm adapted to be operated by fluid under pressure, and a member mounted on one side of said diaphragm for controlling the operation thereof, said member having two substantially parallel base portions of different areas for engaging said diaphragm, one of said portions being always in engagement with the diaphragm and the periphery of the other portion being adapted to engage with the diaphragm when the diaphragm is flexed.

In testimony whereof I have hereunto set my hand, this 16th day of June, 1930.

15 CECIL S. KELLEY.
